UNITED STATES PATENT OFFICE.

IRVING KULIK, OF BROOKLYN, NEW YORK.

X-RAY MOUNT.

Application filed September 30, 1922. Serial No. 591,491.

To all whom it may concern:

Be it known that I, IRVING KULIK, a citizen of the United States, residing at New York city, borough of Brooklyn, 5 county of Kings, and State of New York, have invented a new and useful X-Ray Mount, of which the following is a specification.

This invention relates generally to a 10 mount for photographic transparencies but in addition is particularly directed to also provide a scientific means for easily pointing out certain points in X-ray pictures.

X-ray pictures are frequently resorted to by 15 dentists and the medical profession generally to determine the exact internal condition of a patient or to definitely locate the seat of some disorder or ailment. It is the practice for the physician or dentist to send 20 the patient to a radiologist who takes the necessary X-ray pictures; staples them to a card and forwards this card to the physician or dentist together with any notations which he wishes to make on the particular case 25 under consideration. The radiologist naturally wishes to be certain that particular points referred to in his diagnosis will be located exactly as he intended when he made the diagnosis. It often happens, for example 30 in an X-ray negative of teeth, that a radiologist will diagnose an infection over a root of a particular tooth. That infection can be anywhere about the root of that tooth. In spite of even a lengthy explanation or 35 diagnosis by the radiologist, the exact location cannot be explained with precision, especially if the infection appears obscure in the X-ray negative. Often, because of this difficulty, the X-ray negative is marked with 40 pen and ink outlines or arrows to show where the infection is. The X-ray negative is thus marred or defaced. Through the use of my invention, by employment of a hereinafter described system of indices 45 with section lines, explanation of diagnosis will be made less difficult and X-ray negatives will not have to be marred or defaced.

The present invention provides an efficient and convenient mount for such an X-ray 50 negative and is so constituted as to not only permit of proper notations as to the doctor's name, case number, patient's name and date, but also contains space for diagnoses, together with means for accurately locating by 55 definite reference any particular point or area of the photographic transparency, so

that the radiologist may inform the doctor or the doctor inform his patient of the exact location of the infection or other disorder as well as the area or areas affected. 60

In its preferred practical form, the mount of this invention embodies a folder comprising two leaves. The center of the front leaf is cut away to form a window and in back of this window is attached a sheet of 65 transparent or translucent material, such as celluloid, secured to the back of the front leaf in such manner as to form a pocket into which the X-ray negative may be slipped. Around the four sides of the window opening and on the front face of the front leaf is a scale or scales and on the front face of the back leaf are delineated a number of lines, certain of which extend in parallel 70 relation to one another and in perpendicular 75 relation to a second series of lines, so as to produce the effect of quadrille ruled lines or section lining on engineers' plotting paper. The spacing of this section lining corresponds to the scale or scales of the window 80 opening, so that when a photographic transparency is associated with the window opening, the folding of the two leaves of the folder into face abutting relation will bring the section lining of the back leaf into 85 operative relation with the scales of the window opening. The folder is preferably made of white relatively light card or bristol board, so that when the parts are folded, as described, and are held up in front of 90 a strong transmitted light, such, for example, as an electric bulb, the light will show through the back leaf and through the photographic transparency, so that the transparency may be viewed from the front 95 while the section lining on the back leaf will also be clearly seen.

By reference to these section lines and the scale of the window, any particular point on the X-ray negative may be clearly identified 100 by numbers or letters and spaces are provided on the folder, preferably on the front face of the back leaf for the notation of this information. That is to say, any particular location may be referred to by numbers or figures in such manner that any other person subsequently inspecting the negative in the same manner will be able to follow the diagnosis and understand exactly what the writer who made the notations desired to convey. 105

I have found by experience that if a

2 photographic transparency is viewed by strong transmitted light through an opening bordered by white or some other color which would be apt to produce a glare, that it is very difficult to read the negative through such an opening, due to the effect of such glare upon the eyes. Accordingly, the window opening of the mount of this invention has a relatively deep dark colored border 10 surrounded by a fine dark line to give the border sharpness of outline. The border is preferably black and the scale is formed in white on this black background. This arrangement enables the scale to be readily seen, but precludes the objectionable glare referred to. I consider the employment of this dark colored border and surrounding line of considerable practical importance, since it enables the rest of the mount to be 20 white and therefore the second leaf is rendered capable of transmitting light through the negative. Moreover, by making a card white or of some other light color, the printing and other notations thereon may be 25 easily read.

Aside from the foregoing considerations, the photographic transparency is preferably also provided with a scale or some other suitable designation which enables it to be 30 properly positioned with respect to the scale of the window opening, so that if the transparency should shift, it may be readily returned to its proper position to enable accurate readings.

35 Features of the invention, other than those adverted to, will be apparent from the hereinafter detailed description and claims, when read in conjunction with the accompanying drawings.

40 The accompanying drawings illustrate one practical embodiment of the invention, but the construction therein shown, is to be understood as illustrative, only, and not as defining the limits of the invention.

45 Figure 1 is a view of the mount in its normal folded position.

Figure 2 shows the mount in open position to disclose the back side of the front leaf and the front side of the back leaf 50 thereof; and,

Figure 3 is a front view of a photographic transparency adapted to be mounted on the folder.

The amount shown in the accompanying 55 drawings consists of a folder embodying a front leaf 1 and a back leaf 2 adapted to be folded on the line 3 in Figure 2 into the position shown in Figure 1. The front leaf 1 is provided at its center with an opening 60 or window 4 and positioned back of this window is a sheet of transparent material 5 of celluloid or other suitable material, which is preferably frosted, so as to diffuse light passing therethrough. The sheet 5 is 65 somewhat larger than the window opening

4 and is secured in face abutting relation to the back of the leaf 1 by means of staples 6 or other convenient means, so as to provide an intermediate pocket adapted to receive a film plate or other photographic transparency 7, which may be in the form of a film, plate or otherwise.

Delineated on the front face of the back leaf 2 in such position as to underlie the window opening 4 is a series of section lines 8, similar to the section lines found on engineers' plotting paper and these lines are so spaced as to cooperate with scales 9 and 10 formed along the longitudinal and lateral edges of the window opening. The 80 scales 9 are for the purpose of illustration shown as embodying a series of graduations successively designated by capital or upper case letters A, B, C, etc., while the scales 9 are formed by graduations successively designated by small or lower case letters a, b, c, etc. Accordingly, when the section lines 8 are brought into cooperative relation with the scales 9 and 10, they avoid ambiguity and facilitate rapid and correct 90 location of any particular point in the area of the window opening. Assume for example, that an X-ray negative is in cooperative relation with the window and the folder is in folded position and is held in front of an 95 electric light bulb. Light from the bulb will be transmitted through the back leaf of the folder, through the celluloid 5 and through the X-ray negative, so that a person viewing the negative by this transmitted 100 light can readily determine any particular point in the negative by reference to the scales 9 and 10 and assisted by the lines 8.

For example, the particular point to be called attention to might be at the inner section of the line passing through the graduations G in Figure 1, and another line passing through the scale graduation e. This particular point may be definitely located by a statement that this location occurs G—e and space is left on the front face 105 of the back sheet 2 for such a notation, which, in Figure 2, is shown as written in said space.

Assume that the X-rayed picture shows 110 an area of infection extending between the lines C—E and between e—g. Space is left on the front face of the back leaf for the notation of such areas as are involved and they may be noted in the present instance 115 as C—E and e—g, as shown in Figure 2.

In practice, X-ray negatives particularly those taken of teeth usually show such teeth substantially life size and are substantially 120 true to scale. Accordingly, if the scales or graduations in the window openings are laid out to a unit of measure, an exact mathematical area or linear measurement can be rapidly calculated. That is to say, if each 125 graduation of the scale 9 is assumed to be 130

one-tenth of an inch apart and each graduation of the scale 10^a corresponding distance apart, a dentist can readily tell the length of a root of a tooth or the extent to 5 which an abscess at the base of such root has progressed, so that in using a pulp broach or other dental instrument, he can be sure that he has reached the base of the difficulty.

10 In practice, the photographic transparency 7 may fit the pocket beneath the back of the window opening tightly, or may be stapled or otherwise secured in place, so that it cannot shift after once being positioned 15 therein. If, however, it is desired to have the transparency removable, some designating mark or scale should be associated with the transparency so that it cannot shift position without such shifting being noted.

20 Thus, in Figure 3 I have shown the front face of a photographic transparency on which is designated scales corresponding to the scales around the window opening. These scales enable the positioning of the 25 transparency in an accurate manner and may be formed directly upon a negative or on a strip or strips of material associated with the negative. Thus the scales or indices on the transparency and about the window 30 may be brought into juxtaposition, letter for letter, when it is desired to take the initial reading and when it is desired at any time to check or to follow such initial reading.

35 In practice, the folder is preferably made white or of some other light pale color, so that light may be transmitted through the back leaf thereof and also to enable writing or printed matter thereon to be easily read.

40 I find it convenient to provide spaces on the front sheet for the writing of the patient's name, the doctor's name, the case number and the date, and additional spaces may be utilized for advertising matter, such as that 45 of the studio in which the pictures are taken. However, when a white or light colored folder is employed, such light color directly adjacent the photographic negative makes it very difficult from an ocular standpoint 50 to properly read the negative, which, for the best results, should be surrounded with a black or relatively dark background or mat. To this end, and in order to employ a white or light colored folder, I surround 55 the window opening with a deep border 11 of some contrasting color, preferably black or dark green so as to set off the negative and render it more easily read. Surrounding the dark border and giving it sharpness 60 of outline is a fine line 12. The scales and graduations 9 and 10 are left light on this black background or mat so that it can be easily read, and I have found that this arrangement is highly beneficial and practical 65 and gives very satisfactory results.

Actual use has demonstrated the efficiency of the mount of this invention in the carrying out of its intended purposes. The radiologist takes the X-ray picture, mounts it in the holder and makes the notations calling 70 attention to particular locations or areas and forwards the mount with attached X-ray picture to the physician or dentist, who is able to see at a glance by following the note of instructions, the exact locations and areas 75 to which attention has been called. He can then diagnose the case under consideration and proceed accordingly and if the patient desires to have information, the doctor or dentist can readily explain by the notations 80 and photographs the exact nature and extent of the patient's trouble. Through the use of my invention the patient or doctor can always have for reference an unmarred negative upon which any particular point 85 can at any time be easily and correctly located. Moreover, by reference to the provided index upon the mount, a patient to whom the names of the parts of the body are unknown can be readily shown the seat of trouble without naming other parts of the body to show the locations, as is ordinarily necessary.

The mounts are made of a size and shape that when folded they can be readily filed 90 in a card index for ready reference and will serve as a permanent record.

The accompanying drawings show the invention in its preferred form, but I am aware that slight modifications may be made 100 in structural details without departing from the spirit or substance of this invention which is to be understood as broadly novel as is commensurate with the appended claims.

Having thus fully described the invention, what I claim as new and desire to secure by Letters Patent is:

1. A mount for photographic transparencies embodying a folder of relatively light colored material adapted to transmit light and comprising two leaves, the front leaf of which is provided with a window opening, means for mounting a photographic transparency in juxtaposition with the window opening, so that said transparency may be viewed by transmitted light, and a relatively dark colored border around the window opening to preclude glare when the transparency is thus viewed.

2. A mount for photographic transparencies embodying a folder of relatively light colored material adapted to transmit light and comprising two leaves, the front leaf of which is provided with a window opening, a pocket associated with the window opening and adapted to support a photographic transparency in juxtaposition with the window, so that said transparency may be viewed by transmitted light, and a rela-

tively dark colored border around the window opening to preclude glare when the transparency is thus viewed.

3. A mount for photographic transparencies embodying a folder of relatively light colored material adapted to transmit light and comprising two leaves, the front leaf of which is provided with a window opening, means for mounting a photographic transparency in juxtaposition with the window opening, so that said transparency may be viewed by transmitted light, and a relatively dark colored border around the window opening to preclude glare when the transparency is thus viewed, and graduated scales along the longitudinal and lateral edges of the window opening, by means of which points on the photographic transparency can be readily and accurately located 20 by reference to such scales.

4. A mount for photographic transparencies embodying a folder of relatively light colored material adapted to transmit light and comprising two leaves, the front leaf of which is provided with a window opening, means for mounting a photographic transparency in juxtaposition with the window opening, so that said transparency may be viewed by transmitted light, a relatively dark colored border around the window opening to preclude glare when the transparency is thus viewed, graduated scales along the longitudinal and lateral edges of the window opening, by means of which 30 points on the photographic transparency can be readily and accurately located by reference to such scales, and designations associated with the photographic transparency adapted to be brought into registration with the scales adjacent the window opening for the purpose of properly positioning the transparency with reference to the window opening.

5. A mount for photographic transparencies embodying a folder of relatively light colored material adapted to transmit light and comprising two leaves, the front leaf of which is provided with a window opening, means for mounting a photographic transparency in juxtaposition with the window opening, so that said transparency may be viewed by transmitted light, a relatively dark colored border around the window opening to preclude glare when the transparency is thus viewed, graduated scales along the longitudinal and lateral edges of the window opening, by means of which 50 points on the photographic transparency can be readily and accurately located by reference to such scales, and cross section lines on the back leaf adapted to be seen through the photographic transparency when the transparency is viewed by transmitted light to facilitate the location of any particular point with reference to the scales.

6. A mount for photographic transparencies embodying a folder of relatively light colored material adapted to transmit light and comprising two leaves, the front leaf of which is provided with a window opening, 70 means for mounting a photographic transparency in juxtaposition with the window opening, so that said transparency may be viewed by transmitted light, a relatively dark colored border around the window opening to preclude glare when the transparency is thus viewed, graduated scales along the longitudinal and lateral edges of the window opening, by means of which points on the photographic transparency can be readily and accurately located by reference to such scales, designates associated with the photographic transparency adapted to be brought into registration with the scales adjacent the window opening for the purpose of properly positioning the transparency with reference to the window opening, and spaces on the folder in which notations of such locations are adapted to be written, so that said point or points on the negative may be readily relocated.

7. A mount for photographic transparencies embodying a folder of relatively light colored material adapted to transmit light and comprising two leaves, the front leaf of which is provided with a window opening, means for mounting a photographic transparency in juxtaposition with the window opening, so that said transparency may be viewed by transmitted light, a relatively dark colored border around the window opening to preclude glare when the transparency is thus viewed, graduated scales along the longitudinal and lateral edges of the window opening, by means of which 90 points on the photographic transparency can be readily and accurately located by reference to such scales, cross section lines on the back leaf adapted to be seen through the photographic transparency when the transparency is viewed by transmitted light to facilitate the correct location of any particular point with reference to the scales, and spaces on the folder in which notations of such locations are adapted to be written, so that said point or points on the negative may be readily relocated.

8. A mount for photographic transparencies provided with a window opening, graduated scales along the longitudinal and lateral edges of said window opening, and means for mounting a photographic transparency in juxtaposition with the window opening, whereby any point in the photographic transparency may be easily and accurately located by reference to said scales.

9. A mount for photographic transparencies provided with a window opening, graduated scales along the longitudinal and lateral edges of said opening, means for de-

tachably supporting a photographic transparency in juxtaposition with the window opening, and designations associated with the photographic transparency for securing proper registration of the transparency with the opening, so that any point in the photographic transparency may be readily and accurately located by reference to said scales when said transparency is viewed by transmitted light.

10. A mount for photographic transparencies provided with a window opening, graduated scales along the longitudinal and lateral edges of the window opening, means for mounting a photographic transparency in juxtaposition with the window opening, so that any point in the photographic transparency can be readily and accurately located by reference to the scales when the transparency is viewed by transmitted light, and a deep dark colored border surrounding the window opening and forming a matte for the transparency for the purpose of facilitating the reading of the transparency by transmitted light.

11. A mount for photographic transparencies embodying a sheet of material provided with a window opening, graduated scales along the longitudinal and lateral edges of the opening, means for mounting on said sheet of material a photographic transparency in juxtaposition with the window open-

ing, and a second sheet of material associated with the first sheet and adapted to transmit light, said second sheet being provided with section lining and adapted to be brought into face abutting relation with the first sheet, so that the photographic transparency may be viewed by light transmitted through the second sheet, and the transparency, whereby the cross section lines on the second sheet will facilitate the location of any point in the photographic transparency with reference to the graduated scales associated with the window opening.

12. A mount for photographic transparencies embodying a light colored sheet of material provided with a window opening, a deep black border around the window opening, graduated scales along the longitudinal and lateral edges of the opening printed in light color, so as to transmit light through the scales, but to preclude the transmission of light through the border, and means for securing a photographic transparency in juxtaposition with the window opening, so that the photographic transparency may be viewed by transmitted light through the window opening and any particular point in the transparency definitely located by means of the graduated scales.

In testimony whereof I have signed the foregoing specification.

IRVING KULIK.
